UNITED STATES PATENT OFFICE.

JESSE L. FERRIS, OF LA CROSSE, WISCONSIN.

THERMOSTATIC VALVE.

Application filed September 30, 1925. Serial No. 59,645.

This invention relates to valves of the type used to control the flow of steam automatically through radiators and the like.

The principal objects of the invention are 5 the provision of a valve of the above type which will be positive in its action, which may be accurately adjusted to regulate the amount of valve lift and thereby adapt the valve for uses where a wide variation in 10 temperature may come about.

To this end the invention contemplates the use of a frame adapted to be secured within the steam chamber of a radiator or the like, said frame carrying a sliding carriage upon 15 which is mounted a series of spring elements capable of compound vertical movement through a differential of temperature. The lowermost spring carries a valve adapted to seat on an aperture in the frame. The carriage is made adjustable on the frame.

The invention further consists in the combination, arrangement and construction of parts herein shown and described.

In the drawings:—

25 Figure 1 is a side elevation partly in section, of one embodiment of my invention.

Fig. 2 is a top plan view of the device of Fig. 1.

Fig. 3 is a detail, partly in section along 30 the line 3—3 of Fig. 1.

Fig. 4 is a side elevation of the device, showing the valve removed from the casing.

Fig. 5 is a sectional plan along the line 5—5 of Fig. 4.

35 Fig. 6 is a detail of the carriage element.

Fig. 7 is a detail of the bracket.

Fig. 8 is a detail of the link.

Fig. 9 is a side elevation, partly in section, 40 of the valve and valve seat.

Fig. 10 is a plan view of the base part of the frame.

Referring now particularly to the form shown in the drawings, at 1 is indicated a casing or steam chamber adapted to be connected to the return pipe of an ordinary radiator in the usual manner.

Within the chamber 1 is located the valve, consisting of a two part frame which includes a base 2 having a screw threaded extension adapted to be threaded to a corresponding hole in the casing 1. The frame part 2 is provided with upwardly extending arms 3 adapted to receive between their flanged edges 4 the end of the complemen-

tary frame 5. Obviously the flanges 4 serve 55 to retain the frame parts 2 and 5 in vertical position and in alinement.

A carriage 6 spaced between the vertical portions 7 of the frame 5 is provided with T-shaped ends having flanges 8 adapted to straddle the vertical portions 7 of the upper frame. A set screw 9 threaded through the top of the frame 5 and secured in the carriage 6 may be used to move the carriage and its assembly up or down, as desirable. 65

Attached to each side of the center of the carriage 6 is a series of thermostatic spring elements composed preferably of superimposed layers of brass and steel with the steel on the outside. Due to the unequal expansion of these two alloys under the same degree of heat, these thermostatic springs tend to expand and straighten out or contract and curl up, as the case may be. Each of these series of valve actuating members may consist of a substantially circular member 10 having one end fixed to the side of the carriage 6, and its other end attached to one end of a substantially semi-circular second spring 11. The opposite end of spring 11 is attached to a third spring 12 and its other end is secured to a bracket 13. The thermostatic springs on each side of the carriage 6 are identical. The two brackets 13 carry between them links 14 secured therein by pins 30 15. A pin 16 mounted transversely of the links 14 pivotally carries the shank 17 of a valve element 18 adapted to seat and unseat upon the seat 19 in the lower frame 2.

It will be noted that upon steam being 35 admitted to the chamber containing the thermostatic elements, the upper spring 10 will tend to uncurl or expand outward, thus throwing its free end downward. The second spring 11 tends to uncurl inward and 40 downward and the third spring 12 in the same manner as spring 10. Thus, a lever action is secured by reason of the compound movement of the springs 10, 11 and 12, which moves the valve 18 up or down a considerable distance for slight variations in 45 temperature. Such a construction makes a decidedly accurate and sensitive valve. 100

The set screw 9 enables the valve 18 to be seated or unseated to make a zero or 50 starting point for any desired temperature.

Obviously the lower frame 2 may be replaced by one as at 2^a having a different

sized aperture for connection with the casting 1 by taking out screws 20 from the ends of the vertical portions 7 of the upper frame. The interchangeable frame base 2^a carries its own valve 18^a constructed in the same manner as the valve 18 but of a different size:

Thus a valve has been provided which may be set at any desired temperature and a rise or fall of temperature from that point will cause the valve to function in an automatic manner, which may be made interchangeable to adapt it to casings of various sizes, and which, by reason of the compound action of the thermostatic elements, will move the valve over a comparatively great vertical distance on a slight temperature change.

I claim:

- 20 1. A thermostatic valve comprising a frame adapted to be contained within a casting, a valve seat surrounding an aperture in said frame, a carriage vertically movable in said frame, thermostatic members mounted on said carriage and a valve carried by said members and adapted to seat on said valve seat.
- 25 2. A thermostatic valve comprising a frame adapted to be contained within a casting, a valve seat surrounding an aperture in said frame, a carriage vertically movable in said frame, thermostatic members mounted on said carriage and a valve carried by said members and adapted to seat

on said valve seat, and means on said frame 35 to vertically move said carriage assembly.

3. A thermostatic valve comprising a frame adapted to be contained within a casting, a valve seat surrounding an aperture in said frame, a carriage vertically movable in said frame, thermostatic members mounted on said carriage and a valve carried by said members and adapted to seat on said valve seat, said thermostatic members comprising a pair of series of differentially 40 expansible elements, each series being fixed to opposite sides of the carriage and movable vertically downward.

4. A thermostatic valve comprising a frame adapted to be contained within a casting, a valve seat surrounding an aperture in said frame, a carriage vertically movable in said frame, thermostatic members mounted on said carriage and a valve carried by said members and adapted to seat 55 on said valve seat, said thermostatic members comprising a series of three expansible elements one above the other, the upper element having one end fixed to said carriage, the lower element having one of its ends attached to a fixture carrying the valve, the middle element having one of its ends attached to the element above and the other end to the element below it.

In testimony whereof, I affix my signature.

JESSE L. FERRIS.
